ABSTRACT OF THE DISCLOSURE

The preparation of 2-(o-aminophenoxy)phenyl 1-substituted-piperidyl or pyrrolidinyl ketones and 2-(o-aminophenylthio)phenyl 1-substituted-piperidyl or pyrrolidinyl ketones by reduction of the corresponding 2-(o-nitrophenoxy) or 2-(o-nitrophenylthio) compounds is described. Other methods are also described for the preparation of the above compounds. These compounds have a physiological effect on the central nervous system thereby making them useful as tranquilizers, hypnotics or anti-depressants.

This application is a continuation-in-part of our application Ser. No. 677,012, filed Oct. 23, 1967, which in turn is a continuation-in-part of our application Ser. No. 542,738, filed Apr. 15, 1966, now abandoned.

This invention relates to new organic compounds. More particularly, it relates to 2-(o-aminophenoxy)phenyl 1-substituted-piperidyl or pyrrolidinyl ketones and 2-(o-aminophenylthio)phenyl 1-substituted-piperidyl or pyrrolidinyl ketones which are pharmacologically active and which may be converted into pharmacologically active 11-substituted-dibenz[b,f][1,4]oxazepines and -thiazepines, respectively.

The novel compounds of the present invention may be illustrated by the formula:

wherein R is selected from the group consisting of hydrogen, lower alkyl and, hydroxy lower alkyl, R₁ is selected from the group consisting of hydrogen and lower alkyl; R₂ and R₃ are selected from the group consisting of hydrogen, lower alkyl, lower alkoxy, lower alkylmercapto, halogen, trifluoromethyl, nitro, di(lower alkyl)sulfamoyl and lower alkanoyl; X is selected from the group consisting of oxygen and sulfur; Y is selected from the group consisting of methylene and ethylene; and non-toxic acid addition salts.

The compounds of the present invention possess valuable central nervous system (CNS) properties at non-toxic doses. As such, they show one or more of the following CNS actions: tranquilizer, hypnotic and/or muscle relaxant type actions, and anti-depressant activity. The compounds have been tested pharmacologically and found to have the above properties which show a desirable wide

2

spread between doses producing depressant or sedative actions or anti-depressant actions and toxic symptoms such as paralysis or lethality. They are also analgesics.

The CNS depressant properties, such as tranquilizer, hypnotic and muscle relaxant type activity, are indicated by several procedures. For example, a test which indicates hypnotic and/or muscle relaxant type activity is represented by the following rod walking test. Groups of 6 mice each are tested for their ability to walk across a horizontal rod in a normal manner after receiving graded intraperitoneal doses of a test compound. A median effective dose, rod walking dose (RWD) is estimated.

A test which indicates tranquilizing activity is represented by a measure of the reduction in motor activity. One-half of the rod walking dose (RWD; see above) is given to a group of 5 mice, and a 5 minute count of motor activity is recorded (actophotometer). Counts of ≥ 250 are considered to indicate a specific reduction (more than two standard deviations) of activity at a dose causing only minimal impairment of neurological function as measured by rod walking ability. Compounds that appeared to reduce motor activity (≥ 250 count) are administered to additional groups of 5 mice at graded doses and tested similarly. The motor depressant dose (MDD) which causes a 50% reduction of motor activity (a count of 250) is estimated. The use of reduced motor activity as a measure of tranquilizing activity has been described by W. D. Gray, A. C. Osterberg and C. E. Rauh, Archives Internationales et de Therapie, vol. 134, p. 198 (1961) and by W. J. Kinnard and C. J. Carr, Journal of Pharmacology and Experimental Therapeutics, vol. 121, p. 354 (1957).

When tested by the above procedures, the following compounds of this invention and conversion products therefrom show the activity indicated in Table I.

TABLE I

		MDD intraperitoneally, mg./kg.	RWD intraperitoneally

	2-(o-aminophenylthio)-5-chlorophenyl 1-methyl-4-piperidyl ketone	9	27
	2-chloro-11-(1-methyl-4-piperidyl)dibenz[b,f][1,4]thiazepine hydrochloride	2	10
45	2-chloro-11-(1-methyl-4-piperidyl)dibenz[b,f][1,4]oxazepine	1	7
	11-(1-methyl-4-piperidyl)dibenz[b,f][1,4]oxazepine	>50	25
	11-(1-methyl-4-piperidyl)dibenz[b,f][1,4]thiazepine	41	8

50 The anti-depressant properties of the compounds of the present invention are determined by measuring their ability to counteract a depression induced in animals by the administration of tetrabenazine hexamine. Graded doses of the active compounds of this invention are administered to groups of 5 mice each, and this is followed by administering a dose of tetrabenazine which is known to markedly depress the exploratory behavior of normal mice. The anti-depressant treated groups show normal exploratory behavior, while the control groups, and groups treated with an ineffective anti-depressant agent, do not show normal exploratory behavior, but show the well known profound depression induced by tetrabenazine. When tested by this procedure at the intraperitoneal doses indicated, the following compounds of this invention and conversion products therefrom show anti-depressant activity as described in Table II:

¹ 3.1 orally.

The compounds of this invention are, in general, oils or low melting solids only slightly soluble in water, but soluble in organic solvents such as methanol, ethanol and the like. They are basic substances which are usually soluble in aqueous mineral acids at room temperature. They form substantially insoluble acid addition salts such as the hydrochloride, sulfate, phosphate, and the like. The present compounds, generally in the form of their salts, may be administered orally or parenterally and when so administered, are effective central nervous system agents. For oral administration the new compounds of this invention may be incorporated with the usual pharmaceutical excipients and used, for instance, in the form of tablets, capsules, dragees, liquids to be administered in drops, emulsions, suspensions and syrups, and in chocolate, candy, chewing gum and the like. They may also be administered in suppositories, and in aqueous solutions for parenteral injection.

The new compounds such as the 2-(o-aminophenoxy)-phenyl 1-substituted-piperidyl or pyrrolidinyl ketones and 2-(o-aminophenylthio)phenyl 1-substituted-piperidyl or pyrrolidinyl ketones of this invention may be prepared by several methods which are described hereinafter. One method may be illustrated as follows:

wherein R, R₁, R₂, R₃, X and Y are as hereinbefore described and A is a halogen of atomic weight less than 80. The requisite 2-(o-aminophenoxy)phenyl 1-substituted-piperidyl or pyrrolidinyl ketones and 2-(o-aminophenylthio)phenyl 1-substituted - piperidyl or pyrrolidinyl ketones (I) are products of the reduction of nitroketones (II), obtained by condensing o-nitrohalobenzenes with 2-hydroxy- or 2-mercapto-5-substituted-phenyl 1-substituted - 4 - piperidyl or pyrrolidinyl ketones (III) which, in turn, are preparable from p-substituted phenols or thiophenols (IV) and isonipecotyl halide hydrohalides (V) in the presence of Friedel-Crafts catalysts such as zinc chloride, aluminum chloride, hydrogen fluoride and the like.

A preferred method for obtaining the novel compounds of this invention is illustrated by their interconversion with the corresponding 11 - substituted-dibenz[b,f][1,4] oxazepines and -thiazepines. This is illustrated by the following scheme:

wherein R, R₁, R₂, R₃, X and Y are as previously described. It has been found that the novel ketones (I) of this invention and the 11-substituted-dibenz[b,f][1,4] oxazepines and -thiazepines (VI) described in our parent copending application identified above, are readily interconverted in dilute aqueous acids; i.e. they form equilibrium mixtures. A preferred embodiment of the invention is illustrated by the following equilibrium diagram:

wherein R, R₃ and X are as previously described. The ketones (Ia) and the dibenz[b,f][1,4]oxazepines and -thiazepines (VIa) are interconverted in the presence of approximately 0.1 N hydrochloric acid. Isolation of either one or both components from mixtures containing (Ia) and (VIa) is dependent upon the individual properties of the equilibrium pair. Physical properties such as differential solubilities of the bases and/or acid addition salts may thus determine which of these components is more readily isolated from a given mixture. The proportions of each component will also vary in the equilibrium mixtures; which also influences the ease of isolation of the desired compound. Standard methods of separation and purification well known to those skilled in the art are used for isolation of the desired products; these include extraction, fractional crystallization, chromatographic separation and purification, and the like.

As shown in the above equilibrium scheme, the 2-(o-aminophenoxy)phenyl 1-substituted-piperidyl ketones and 2-(o-aminophenylthio)phenyl 1-substituted-piperidyl ketones (I) of this invention may be obtained together with the dibenz[b,f][1,4]oxazepines and -thiazepines (VIa), or in some instances may be the sole product isolated, when a suitably substituted 2'-aryloxy- or 2'-arylthio substituted anilide (VIIa) is cyclized to the corresponding dibenz[b,f][1,4]oxazepine or -thiazepine (VIa)

5

followed by treatment with aqueous acid as shown with the following preferred embodiment:

wherein R, R₃ and X are as hereinbefore defined.

Using the above method, appropriately substituted isonipecotanilides are treated with acidic condensing agents such as phosphorus oxychloride; phosphorus pentachloride, polyphosphoric acid, zinc chloride, aluminum chloride and the like either alone or in combination or in the presence of an inert solvent such as benzene, xylene, o-dichlorobenzene and the like. This reaction is generally carried out at an elevated temperature but the temperature may range from about 90° C. to about 240° C. The reaction is usually complete within several hours but may take as long as 2 to 4 days with mild reagents at low temperatures. The required substituted isonipecotanilides, nipecotanilides, pipercolinilides, etc. are readily prepared by acylation of known o-aryloxyanilines and o-arylthioanilines with the desired substituted acid halide hydrohalide. This reaction is generally effected in an inert solvent such as acetone, benzene, dimethylformamide and the like in the presence of an alkaline reagent such as triethylamine, pyridine, dimethylaniline, and the like.

Cyclization of the 2-(o-aminophenoxy)phenyl 1-substituted-4-piperidyl or pyrrolidinyl ketones and 2-(o-aminophenylthio)phenyl 1-substituted-4-piperidyl or pyrrolidinyl ketones (Ia) of this invention to the corresponding 11-substituted-dibenzo[b,f][1,4]oxazepines and -thiazepines (VIa) may also be carried out under anhydrous conditions in an inert solvent such as benzene, toluene, xylene and the like. Reagents such as zinc chloride, sulfuric acid, p-toluenesulfonic acid, phosphorus pentachloride, phosphorus pentoxide and the like are suitable for this purpose. The temperature range for carrying out this reaction is from about 80° C. to 150° C. The cyclized dibenz[b,f][1,4]oxazepines and -thiazepines obtained therefrom are also valuable pharmaceutical products. In general, the individual ketone products (Ia) of this invention and the corresponding 11-piperidyl-dibenzo[b,f][1,4]-oxazepine (or -thiazepine) cyclization product (VIa) both show similar activities; i.e. both show antidepressant activity of a similar order, or both show CNS depressant properties. Thus, a further advantage of the compounds of this invention is their conversion into other products which also show excellent pharmaceutical properties.

DETAILED DESCRIPTION

The following examples illustrate in detail the various methods of preparing 2-(o-aminophenoxy)phenyl 1-substituted-piperidyl or pyrrolidinyl ketones and 2-(o-aminophenylthio)phenyl 1-substituted-piperidyl or pyrrolidinyl ketones of the present invention.

6

EXAMPLE 1

Preparation of 2-(o-aminophenylthio)-5-chlorophenyl 4-piperidyl ketone

The crude hydrobromide salt of 2'-(p-chlorophenylthio)isonipecotanilide, prepared from 2.4 g. of benzyl 4-[o-(p-chlorophenylthio)phenyl]carbamoylpiperidine-1-carboxylate stirred for 15 minutes with 15 ml. of 48% hydrogen bromide in glacial acetic acid and concentrated, is cyclized with polyphosphoric acid as described in Example 2.

The above reaction solution is stirred and quenched with ice (exothermic reaction at the ice-phosphoric acid solution interface), made basic with concentrated potassium hydroxide, and the resulting aqueous-solid mixture is extracted with ether. The ether extract is dried and concentrated to give 0.65 g. (27%) of the anilino-ketone. Two recrystallizations from ether give pure 2-(o-aminophenylthio)-5-chlorophenyl 4-piperidyl ketone, M.P. 149-152° C., UV_{max} 345 m μ (ϵ 3300), 310 m μ (ϵ 4700), 270 m μ (ϵ 8700), 235 m μ (ϵ 26,000), I.R. (KBr) 2.93 and 3.04 μ (NH₂), 5.96 μ (ketone C=O); NMR (CDCl₃) ca. δ 1.8-2.1 (m, 4, C(CH₂)₂),

δ 2.4 (s, 3, N—CH₃), ca. δ 2.8-3.2 (m, 4, N(CH₂)₂), δ 2.25 (s, 2, NH₂), ca. δ 6.7-7.7 (m, 7, aromatic).

Analysis.—Calcd. for C₁₈H₁₉ClN₂OS (percent): C, 62.3; H, 5.5; Cl, 10.2; N, 8.1; S, 9.2. Found (percent): C, 61.4; H, 5.5; Cl, 10.3; N, 8.0; S, 9.0.

EXAMPLE 2

Preparation of 2-(o-aminophenylthio)-5-chlorophenyl 4-piperidyl ketone

The hydrochloride salt of 3.5 g. (0.01 mole) of 2'-(p-chlorophenylthio)isonipecotanilide in 130 g. of polyphosphoric acid is heated for 7 hours at 163° C. The reaction is cooled and placed in a water saturated atmosphere overnight (initial quenching). Ice is added to the reaction solution while externally cooling with an acetone-ice bath. The resulting mixture (600 ml.) is treated with activated charcoal and 10% potassium hydroxide solution is added to the filtrate (to pH 9; <15°) which precipitates a semi-solid. This suspension is extracted with ether and evaporation of the ether extract gives 0.45 g. (14%) of the desired cyclized product, M.P. 157-162° C. (as the base). Recrystallization from ethyl acetate gives 200 mg. of 2-chloro-11-(4-piperidyl)dibenzo[b,f][1,4]thiazepine, M.P. 167-169° C., I.R. (KBr) 6.14 μ (anil C=N).

The above aqueous suspension, after extraction with ether, is re-extracted with methylene chloride to give 2.7 g. of a semi-solid residue. A portion of the crude product (2.4 g.) is stirred in a mixture of ether and 10% sodium hydroxide (three phase system) for 3 hours during which all of the solid dissolves. The phases are separated and the ether phase is concentrated to dryness to give an additional 1.2 g. of 2-chloro-11-(4-piperidyl)dibenzo[b,f][1,4]thiazepine, M.P. 157-162° C. This is combined with the recrystallized base isolated from the ether extract (0.2 g., M.P. 167-169° C.), dissolved in a minimum amount of hot ethanol, and treated with one equivalent of ethanolic hydrogen chloride. After 4 days of refrigeration (0-5° C.) the precipitate is filtered and dried to give 0.8 g. (22%, overall yield) of 2-chloro-11-(4-piperidyl)dibenzo[b,f][1,4]thiazepine hydrochloride UV_{max} (MeOH) 340 m μ (ϵ 1300), 303 m μ (ϵ 2200); (KBr) 6.14 μ (anil C=N).

A 100 mg. portion of the original 2.7 g. semi-solid residue is dissolved in 0.1 N hydrochloric acid and filtered. The filtrate is washed with ether and made alkaline with

30% potassium hydroxide. The oily precipitate which forms is extracted into ether and concentrated to dryness. The residue, 39 mg., has an I.R. spectrum (5.96 μ ; ketone C=O) identical to that of purified 2-(o-aminophenylthio)-5-chlorophenyl 4-piperidyl ketone.

EXAMPLE 3

Preparation of 2-(o-aminophenylthio)-5-chlorophenyl 1-methyl-4-piperidyl ketone

Five-and-four-tenths grams (0.015 mole) of 2'-(p-chlorophenylthio)-1-methylisonicotanilide is cyclized in 152 g. (30:1 by weight) of polyphosphoric acid. The reaction is worked up as described in Example 2. Two recrystallizations from hexane give 17% of 2-(o-aminophenylthio)-5-chlorophenyl 1-methyl-4-piperidyl ketone, M.P. 124-125° C., UV_{max} 350 μ (ϵ 3100), 311 m μ (ϵ 4900), 270 m μ (ϵ 8700), 235 m μ (ϵ 25,400); I.R. (KBr) 2.93 μ and 3.04 μ (NH₂), 5.99 μ (ketone C=O).

Analysis.—Calcd. for C₁₉H₂₁ClN₂SO (percent): C, 63.2; H, 5.9; Cl, 9.8; N, 7.8; S, 8.9. Found (percent): C, 63.6; H, 6.2; Cl, 10.0; N, 7.7; S, 9.0.

EXAMPLE 4

Preparation of 2-(o-aminophenoxy)phenyl 4-piperidyl ketone

2'-phenoxyisonicotanilide (6.7 g.) is converted to the oily hydrochloride with ethanolic hydrogen chloride and heated at 178° C. for 7 hours with 210 g. of polyphosphoric acid. The mixture is cooled, stored at 0-5° C. overnight in a water-saturated atmosphere and poured onto 700 g. of ice with stirring. The resulting mixture is filtered, treated with methylene chloride and then kept cold (0-15° C.) while adjusting the pH to 9-10 with 20% potassium hydroxide. The mixture is stirred overnight, the methylene chloride layer is separated and dried over potassium carbonate. Concentration yields 5.4 g. of a mixture of the desired product together with 11-(4-piperidyl)dibenz[b,f][1,4]oxazepine. This mixture in methylene chloride is treated with hydrogen chloride to yield the less soluble 2-(o-aminophenoxy)phenyl 4-piperidyl ketone as the dihydrochloride, M.P. 268-272° C.; I.R. (KBr) 3.5-4.5 (-NH₃⁺ and >NH₂⁺) 5.95 (C=O), 6.25 μ ; UV λ_{max} (MeOH) 293 m μ (ϵ 3700); NMR [(eD₃)₂SO] 89.6, 8.7 (two broad peaks, 5H total, >NH₂⁺ and -NH₃⁺); differential thermal analysis, endotherm at ca. 150° C. (9.5% loss in weight, loss of HCl), melting point ca. 250° C. (weight loss, decomposition); mass spectrum (70 ev.) m/e 296, 278 (probe 122°), m/e 278 (probe 265°).

The more soluble 11-(4-piperidyl)dibenz[b,f][1,4]oxazepine hydrochloride is isolated by cooling the filtrate for several days and collecting the precipitated product; melting point 260-261° C. 1 I.R. (KBr) 3.4-4.6

(>NH₂⁺), 6.2 μ (acid C=N); UV λ_{max} (MeOH) 322 m μ (ϵ 3,200); NMR ((CD₃)₂SO) δ 9.6 (ca. 2H, >NH₂⁺)

differential thermal analysis, melting point ca. 230° C. (wt. loss, decomposition).

EXAMPLE 5

Preparation of 2-(o-aminophenylthio)phenyl 1-methyl-4-piperidyl ketone

A solution of 20 mg. of 11-(1-methyl-4-piperidyl)-dibenz[b,f][1,4]thiazepine in 10 ml. of 0.1 N hydrochloric acid is prepared and, after 30 minutes for equilibration, is added to 1 ml. of 30% potassium hydroxide. The mixture of anilino ketone and acid is extracted with ether and dried over potassium carbonate. The ether is removed and the residue chromatographed on fluorescent silica gel using the upper phase of a 1:2:2 mixture of benzene:acetone:water containing 5% triethylamine. Elution of the less polar UV-absorbing spot with 5% concentrated ammonium hydroxide in methanol and concentration gives

recovered 11-(1-methyl-4-piperidyl)dibenz[b,f][1,4]thiazepine.

Similar elution of the more polar spot yields 2-(o-aminophenylthio)phenyl 1-methyl-4-piperidyl ketone, which has infrared absorption at 6.0 and 3.15 μ .

EXAMPLE 6

Preparation of 5-chloro-2-(o-aminophenylthio)phenyl 4-piperidyl ketone

10 A solution of 20 mg. of 2-chloro-11-(4-piperidyl)dibenz[b,f][1,4]thiazepine hydrochloride in 10 ml. of 0.1 N hydrochloric acid is prepared and, after 30 minutes for equilibration, is added to 1 ml. of 30% potassium hydroxide. The mixture of anilino ketone and acid is extracted with ether and dried over potassium carbonate. The ether is removed and the residue chromatographed on fluorescent silica gel using the upper phase benzene:acetone:water system containing triethylamine. Elution of the less polar UV-absorbing spot with 5% concentrated ammonium hydroxide in methanol and concentration gives recovered 2-chloro-11-(4-piperidyl)dibenz[b,f][1,4]thiazepine with infrared absorption at 6.1 μ . Similar elution of the more polar spot yields 5-chloro-2-(o-aminophenylthio)phenyl 4-piperidyl ketone which has infrared absorption at 6.0 and 3.1 μ .

EXAMPLE 7

Preparation of 2-(o-aminophenoxy)phenyl 1-methyl-4-piperidyl ketone

30 A solution of 20 mg. of 11-(1-methyl-4-piperidyl)-dibenz[b,f][1,4]oxazepine in 10 ml. of 0.1 N hydrochloric acid is prepared and, after 30 minutes for equilibration, is added to 1 ml. of 30% potassium hydroxide. The mixture of anilino ketone and acid is extracted with ether and dried over potassium carbonate. The ether is removed and the residue chromatographed on fluorescent silica gel using the upper phase benzene:acetone:water system containing triethylamine. Elution of the benzene polar UV-absorbing spot with 5% concentrated ammonium hydroxide in methanol and concentration gives recovered 11-(1-methyl-4-piperidyl)dibenz[b,f][1,4]oxazepine with infrared absorption at 6.2 μ . Similar elution of the more polar spot yields 2-(o-aminophenoxy)phenyl 1-methyl-4-piperidyl ketone, which has infrared absorption at 6.0 and 3.2 μ .

EXAMPLE 8

Preparation of 2-chloro-11-(4-piperidyl)dibenz[b,f][1,4]thiazepine

50 Thirty-nine milligrams of 2-(o-aminophenylthio)-5-chlorophenyl 4-piperidyl ketone (Example 1) in a suspension of phosphorus pentoxide in benzene is heated to reflux. After four days the suspension is cooled, the solvent decanted and methylene chloride is added to the residue followed by quenching with ice. The mixture is adjusted to an alkaline pH with 10% sodium hydroxide. The phases are separated and concentration of the organic phase gives an oil which crystallizes (ca. 20 mg.), melting point 157-162° C., with the same I.R. spectrum as 2-chloro-11-(4-piperidyl)dibenz[b,f][1,4]thiazepine (base).

EXAMPLE 9

Preparation of 11-(4-piperidyl)dibenz[b,f][1,4]oxazepine sulfate

65 A solution of 3.1 mg. of 2-(o-aminophenoxy)phenyl-4-piperidyl ketone dihydrochloride (Example 4) in 0.2 ml. of water is treated with 48 mg. of sodium sulfate and warmed to ca. 40° C. for 15 minutes. Cooling gives crystalline 11-(4-piperidyl)-dibenz[b,f][1,4]oxazepine sulfate which has infrared absorption at 3.6, 4.0, 6.2 and 8.9 μ .

EXAMPLE 10

Preparation of 2-(o-aminophenylthio)-5-chlorophenyl 1-methyl-4-piperidyl ketone

p-Chlorothiophenol and 1-methylisonipecotoyl chloride hydrochloride are condensed in the presence of aluminum chloride to give 2-mercaptop-5-chlorophenyl 1-methyl-4-piperidyl ketone. This intermediate is treated with o-chloronitrobenzene and 2-(o-nitrophenoxythio)-5-chlorophenyl 1-methyl-4-piperidyl ketone is obtained. Reduction with zinc and aqueous ethanolic ammonium chloride then gives the desired product, 2-(o-aminophenylthio)-5-chlorophenyl 1-methyl-4-piperidyl ketone.

EXAMPLE 11

Preparation of 2-(o-aminophenoxy)phenyl 1-methyl-4-piperidyl ketone

Phenol and 1-methylisonipecotoyl chloride hydrochloride are condensed in the presence of ammonium chloride to give o-hydroxyphenyl 1-methyl-4-piperidyl ketone. This intermediate is treated with o-chloronitrobenzene and 2-(o-nitrophenoxy)phenyl 1-methyl-4-piperidyl ketone is obtained. Reduction with zinc and aqueous ethanolic ammonium chloride then gives the desired product, 2-(o-aminophenoxy)phenyl 1-methyl-4-piperidyl ketone.

EXAMPLE 12

The procedure described in Example 5 is repeated. The appropriate 11-substituted dibenz[b,f][1,4]oxazepines and thiazepines are equilibrated in dilute hydrochloric acid and the resulting 2-(o-aminophenoxy)phenyl 1-substituted-4-piperidyl ketone or 2-(o-aminophenylthio)-phenyl-1-substituted-4-piperidyl ketone is obtained after separation from unreacted starting material as follows:

Dibenz[b,f][1,4]oxazepine (or thiazepine)	Ketone
2-chloro-11-(1-methyl-4-piperidyl)dibenz[b,f][1,4]oxazepine.	2-(o-aminophenoxy)-5-chlorophenyl 1-methyl-4-piperidyl ketone.
2-chloro-11-(1-methyl-4-piperidyl)dibenz[b,f][1,4]thiazepine.	2-(o-aminophenylthio)-5-chlorophenyl 1-methyl-4-piperidyl ketone.
2-chloro-11-(4-piperidyl)dibenz[b,f][1,4]oxazepine.	2-(o-aminophenoxy)-5-chlorophenyl 4-piperidyl ketone.
11-(4-piperidyl)dibenz[b,f][1,4]thiazepine.	2-(o-aminophenylthio)phenyl-4-piperidyl ketone.
2-chloro-11-(1-(2-hydroxyethyl)-4-piperidyl)dibenz[b,f][1,4]oxazepine.	2-(o-aminophenoxy)-5-chlorophenyl 1-(2-hydroxyethyl)-4-piperidyl ketone.
11-(1-methyl-4-piperidyl)dibenz[b,f][1,4]thiazepine.	2-(o-aminophenylthio)phenyl 1-methyl-4-piperidyl ketone.
11-(1-methyl-4-piperidyl)-2-trifluoromethyldibenz[b,f][1,4]oxazepine.	2-(o-aminophenoxy)-5-trifluoromethylphenyl 1-methyl-4-piperidyl ketone.
2-bromo-11-(1-methyl-4-piperidyl)dibenz[b,f][1,4]thiazepine.	2-(o-aminophenylthio)-5-bromophenyl 1-methyl-4-piperidyl ketone.
2-fluoro-11-(1-methyl-4-piperidyl)dibenz[b,f][1,4]thiazepine.	2-(o-aminophenylthio)-5-fluorophenyl 1-methyl-4-piperidyl ketone.
2-(N,N-dimethylsulfamoyl)-11-(1-methyl-4-piperidyl)dibenz[b,f][1,4]oxazepine.	2-(o-aminophenoxy)-5-(N,N-dimethylsulfamoyl)phenyl 1-methyl-4-piperidyl ketone.
3-acetyl-11-(1-methyl-4-piperidyl)dibenz[b,f][1,4]oxazepine.	2-(o-aminophenoxy)-5-acetylphenyl 1-methyl-4-piperidyl ketone.
2-methoxy-11-(1-methyl-4-piperidyl)dibenz[b,f][1,4]oxazepine.	2-(o-aminophenoxy)-5-methoxyphenyl 1-methyl-4-piperidyl ketone.
11-(1-methyl-4-piperidyl)-2-methylthiodibenz[b,f][1,4]oxazepine.	2-(o-aminophenoxy)-5-methylthiophenyl 1-methyl-4-piperidyl ketone.
2-chloro-3-methyl-11-(1-methyl-4-piperidyl)dibenz[b,f][1,4]thiazepine.	2-(3-amino-p-tolylthio)phenyl 1-methyl-4-piperidyl ketone.
8-methyl-11-(1-methyl-4-piperidyl)dibenz[b,f][1,4]thiazepine.	2-(3-amino-p-tolylthio)phenyl 1-methyl-4-piperidyl ketone.
2-chloro-11-(1-methyl-4-propyl-4-piperidyl)dibenz[b,f][1,4]thiazepine.	2-(o-aminophenylthio)-5-chlorophenyl 1-methyl-4-propyl-4-piperidyl ketone.
2-chloro-11-(1-methyl-3-pyrrolidinyl)dibenz[b,f][1,4]oxazepine.	2-(o-aminophenoxy)-5-chlorophenyl 1-methyl-3-pyrrolidinyl ketone.
2-chloro-11-(1-methyl-3-piperidyl)dibenz[b,f][1,4]thiazepine.	2-(o-aminophenylthio)-5-chlorophenyl 1-methyl-3-piperidyl ketone.
2-chloro-11-(1-methyl-2-piperidyl)dibenz[b,f][1,4]thiazepine.	2-(o-aminophenylthio)-5-chlorophenyl 1-methyl-2-piperidyl ketone.
11-(6-methyl-3-piperidyl)dibenz[b,f][1,4]oxazepine.	2-(o-aminophenoxy)phenyl-6-methyl-3-piperidyl ketone.
11-(1-methyl-4-piperidyl)-2-nitrodibenz[b,f][1,4]oxazepine.	2-(o-aminophenoxy)-5-nitrophenyl 1-methyl-4-piperidyl ketone.

EXAMPLE 13

Preparation of 2-chloro 11-(1-methyl-4-piperidyl)dibenz[b,f][1,4]oxazepine

A slurry of 1-methylisonipecotoyl chloride hydrochloride is prepared by the reaction of thionyl chloride (25 ml.) and 9.7 g. of 1-methylisonipecotic acid, hydrochloride at 25° C. After the evolution of gas ceases, the excess thionyl chloride is removed by distillation under reduced pressure. The crystalline residue is triturated with 250 ml. of anhydrous hexane. The resulting suspension is concentrated to dryness under reduced pressure (thereby removing solvent and residual thionyl chloride). This residue is then taken up in 200 ml. of anhydrous acetone. To this slurry is added 10.4 g. of 2-(p-chlorophenoxy)-aniline in 50 ml. of acetone. After 20 minutes, 10 g. of triethylamine is added, with the immediate formation of a heavy slurry. After stirring for 2 hours at room temperature, the reaction mixture is filtered and the filtrate is concentrated to dryness. The residue is dissolved in a benzene-water mixture and the aqueous phase is made basic with potassium carbonate. The product is extracted into benzene and the benzene layer is dried over potassium carbonate and concentrated under reduced pressure. Recrystallization from hexane then gives 2'-(p-chlorophenoxy)-1-methylisonipecotanilide, melting point 141°-143° C.

The hydrochloride salt of 2'-(p-chlorophenoxy)-1-methylisonipecotanilide is prepared by dissolving 0.7 g. of the base in ethanol containing an excess of hydrochloric acid. The resulting solution is concentrated to dryness. To the residue is added 1.4 g. of phosphorus pentoxide and 5 ml. of phosphorus oxychloride. The mixture is refluxed for 48 hours, after which it is quenched with ice and made alkaline with potassium hydroxide. The semi-solid product is collected, and is dried in vacuum over phosphorus pentoxide. This semi-solid product is purified by adsorption chromatography on an alumina column. The purified product is eluted from the column using an ethyl acetate-hexane solvent system. Removal of the solvent then gives 2-chloro-11-(1-methyl-4-piperidyl)dibenz[b,f][1,4]oxazepine as a clear, colorless oil. The ultraviolet absorption spectrum of this material shows

$\lambda_{\text{max}}^{\text{CH}_3\text{OH}} 300, 325 \text{ m}\mu (\epsilon = 5200, 5500, \text{ respectively})$

Treatment of an ether solution of this base with alcoholic hydrogen chloride precipitates a hydrochloride salt of the product, melting point 246-249° C.

Alternatively, the above-described cyclization is also effected using a mixture of phosphorus oxychloride and polyphosphoric acid or polyphosphoric acid alone in place of the mixture of phosphorus pentoxide and phosphorus oxychloride.

EXAMPLE 14

Preparation of 2-chloro-11-(1-methyl-4-piperidyl)dibenz[b,f][1,4]thiazepine hydrochloride

To a suspension of 1-methylisonipecotoyl chloride hydrochloride, prepared by the procedure used in Example 13, in acetone is added 2-(p-chlorophenoxythio)aniline. After 20 minutes, two equivalent of dimethylaniline is added with the immediate formation of a heavy precipitate. After stirring overnight the dimethylaniline hydrochloride is removed by filtration. The filtrate is concentrated to dryness and the residue is recrystallized from hexane to give 2'-(p-chlorophenoxythio)-1-methylisonipecotanilide, melting point 126-128° C.

The hydrochloride salt of 2'-(p-chlorophenoxythio)-1-methylisonipecotanilide is prepared with ethanolic hydrochloric acid. This compound is treated with polyphosphoric acid at 170° C. for 8 hours, after which it is quenched on ice and made alkaline. The product is extracted into ether, dried with potassium carbonate and concentrated to dryness. The oily residue is dissolved in ethanol containing an equivalent amount of hydrochloride acid and the addi-

11

tion of ether precipitates 2-chloro-11-(1-methyl-4-piperidyl)dibenzo[b,f][1,4]thiazepine hydrochloride, melting point 234-237° C.

EXAMPLE 15

Preparation of 11-(1-methyl-4-piperidyl)dibenzo[b,f][1,4]oxazepine

The compound o-phenoxyaniline is treated with 1-methylisonipecotyl chloride hydrochloride by the procedure of Example 14 to give 1-methyl-2'-phenoxyisonipecotanilide.

This compound is cyclized with phosphorus pentoxide and phosphorus oxychloride according to the procedure of Example 1 to give 11-(1-methyl-4-piperidyl)dibenzo[b,f][1,4]oxazepine. Hydrogenolysis of 2-chloro-11-(1-methyl-4-piperidyl)dibenzo[b,f][1,4]oxazepine with palladium in ethanol gives 11-(1-methyl-4-piperidyl)dibenzo[b,f][1,4]oxazepine hydrochloride, melting point 230-35° C.

EXAMPLE 16

Preparation of 11-(1-methyl-4-piperidyl)dibenzo[b,f][1,4]thiazepine

The compound o-phenylthioaniline is reacted with 1-methylisonipecotyl chloride hydrochloride as in Example 14 to give 1-methyl-2'-(phenylthio)isonipecotanilide.

The latter compound is cyclized with polyphosphoric acid according to the procedure of Example 14 to give 11-(1-methyl-4-piperidyl)dibenzo[b,f][1,4]thiazepine.

EXAMPLE 17

Preparation of 2-chloro-11-(4-piperidyl)dibenzo[b,f][1,4]oxazepine

1-carbobenzyloxy-2'-(p-chlorophenoxy)isonipecotanilide is prepared by treating a solution of 1-carbobenzyloxyisonipecotic acid in tetrahydrofuran with carbonyldiimidazole at 10° C., followed by the addition of o-(p-chlorophenoxy)aniline.

This compound is cyclized with phosphorus pentoxide and phosphorus oxychloride according to the procedure of Example 13 to give 2-chloro-11-(4-piperidyl)dibenzo[b,f][1,4]oxazepine. 2-chloro-11-(4-piperidyl)dibenzo[b,f][1,4]oxazepine is also prepared by cleavage of 11-(1-carbobenzyloxy-2-(4-piperidyl)-2-chlorodibenzo[b,f][1,4]oxazepine with hydrobromic acid in glacial acetic acid. The hydrochloride has melting point 273-5° C.

EXAMPLE 18

Preparation of 11-(4-piperidyl)dibenzo[b,f][1,4]thiazepine

1-carbobenzyloxy-2'-(phenylthio)isonipecotanilide is prepared by treating a solution of 1-carbobenzyloxyisonipecotic acid in tetrahydrofuran with carbonyldiimidazole at 10° C. followed by the addition of o-(phenylthio)aniline. The mixture is refluxed for 1 hour and the product is isolated.

This compound is cyclized with polyphosphoric acid according to the procedure of Example 14 to give 11-(4-piperidyl)dibenzo[b,f][1,4]thiazepine.

EXAMPLE 19

Preparation of 2-chloro-11-[1-(2-hydroxyethyl)-4-piperidyl]dibenzo[b,f][1,4]oxazepine

2-(p-chlorophenoxy)aniline is treated with the α -lactone of α -hydroxy- α -(2-hydroxyethyl)butyric acid to give 2'-(p-chlorophenoxy)-4-hydroxy-2-(2-hydroxyethyl)butyranilide. This compound is refluxed with phosphorus pentoxide and phosphorus oxychloride according to the procedure of Example 13 to give 2-chloro-11-[bis(2-chloroethyl)methyl]dibenzo[b,f][1,4]oxazepine hydrochloride. Treatment of 2-chloro-11-[bis(2-chloroethyl)methyl]dibenzo[b,f][1,4]oxazepine hydrochloride with aminoethanol yields the desired compound 2-chloro-11-

[1-(2-hydroxyethyl)-4-piperidyl]dibenzo[b,f][1,4]oxazepine.

Treatment of 2-chloro-11-(4-piperidyl)dibenzo[b,f][1,4]oxazepine with ethylene oxide gives the same compound, 2-chloro-11-[1-(2-hydroxyethyl)-4-piperidyl]dibenzo[b,f][1,4]oxazepine.

EXAMPLE 20

Preparation of 11-(1-methyl-4-piperidyl)-2-trifluoromethyl-dibenzo[b,f][1,4]oxazepine

2-(α , α , α -trifluoro-p-tolyloxy)aniline is treated with 1-methylisonipecotyl chloride hydrochloride by the procedure of Example 14 to give 1-methyl-2'-(α , α , α -trifluoro-p-tolyloxy)isonipecotanilide. This compound is treated with phosphorus pentoxide and phosphorus oxychloride according to the procedure of Example 13 to give 11-(1-methyl-4-piperidyl)-2-trifluoromethyl-dibenzo[b,f][1,4]oxazepine.

EXAMPLE 21

Preparation of 2-bromo-11-(1-methyl-4-piperidyl)dibenzo[b,f][1,4]thiazepine

The methods of Example 14 are repeated. Thus, 2-(p-bromophenylthio)aniline is acylated with 1-methylisonipecotyl chloride hydrochloride to give 2'-(p-bromophenylthio)-1-methyl-isonipecotanilide as in Example 14. This compound is cyclized in hot polyphosphoric acid, as in Example 14, to give 2-bromo-11-(1-methyl-4-piperidyl)dibenzo[b,f][1,4]thiazepine.

EXAMPLE 22

Preparation of 2-fluoro-11-(1-methyl-4-piperidyl)dibenzo[b,f][1,4]thiazepine

The methods of Example 14 are repeated. Thus, 2-(p-fluorophenylthio)aniline is acylated with 1-methylisonipecotyl chloride hydrochloride to give 2'-(p-fluorophenylthio)-1-methyl-isonipecotanilide, as in Example 14. This compound is cyclized in hot polyphosphoric acid, as in Example 14, to give 2-fluoro-11-(1-methyl-4-piperidyl)dibenzo[b,f][1,4]thiazepine.

EXAMPLE 23

Preparation of 2-(N,N-dimethylsulfamoyl)-11-(1-methyl-4-piperidyl)dibenzo[b,f][1,4]oxazepine

o-(p-(N,N-dimethylsulfamoyl)phenoxy)aniline is treated with 1-methylisonipecotyl chloride hydrochloride by the procedure of Example 13 to give 2'-(p-(N,N-dimethylsulfamoyl)phenoxy)-1-methyl-isonipecotanilide. The hydrochloride has melting point 255-260° C. This compound is cyclized with phosphorus oxychloride according to the procedure of Example 13 to yield 2-(N,N-dimethylsulfamoyl)-11-(1-methyl-4-piperidyl)dibenzo[b,f][1,4]oxazepine. The hydrochloride has melting point 260-264° C. (decomposition).

EXAMPLE 24

Preparation of 3-acetyl-11-(1-methyl-4-piperidyl)dibenzo[b,f][1,4]oxazepine

The compound o-(m-acetylphenoxy)aniline is treated with 1-methylisonipecotyl chloride hydrochloride by the procedure of Example 14 to give 2'-(m-acetylphenoxy)-1-methyl-isonipecotanilide. This compound is cyclized with phosphorus pentoxide and phosphorus oxychloride according to the procedure of Example 13 to yield 3-acetyl-11-(1-methyl-4-piperidyl)dibenzo[b,f][1,4]oxazepine.

EXAMPLE 25

Preparation of 2-methoxy-11-(1-methyl-4-piperidyl)dibenzo[b,f][1,4]oxazepine

Hydroquinone monomethyl ether is acylated with 1-methylisonipecotic acid under Friedel-Crafts conditions in the presence of anhydrous hydrogen fluoride. The resulting 2-hydroxy-5-methoxyphenyl-4-piperidyl ketone is condensed with o-chloronitrobenzene in the presence of

13

potassium carbonate and copper powder, and the resulting nitro compound is hydrogenated over palladium on charcoal in ethanol to give 2-(o-aminophenoxy)-5-methoxy-phenyl-1-methyl-4-piperidyl ketone. This compound is heated in xylene in the presence of zinc chloride to give 2-methoxy-11-(1-methyl - 4 - piperidyl)dibenzo[b,f][1,4]oxazepine.

The same compound is obtained when o-(p-methoxy-phenoxy)aniline is heated with 1-methylisonipecotoyl chloride hydrochloride by the procedure of Example 14 to give 2'-(p-methoxyphenoxy) - 1 - methylisonipecotanilide which is cyclized with phosphorus pentoxide and phosphorus oxychloride according to the procedure of Example 13 to yield 2-methoxy-11-(1-methyl-4-piperidyl)dibenzo[b,f][1,4]oxazepine.

EXAMPLE 26

Preparation of 11-(1-methyl-4-piperidyl)-2-methyl-thiobenz[b,f][1,4]oxazepine

o - (p - Methylthiophenoxy)aniline is treated with 1-methylisonipecotoyl chloride hydrochloride by the procedure of Example 14 to give 2'-(p-methylthiophenoxy)-1-methylisonipecotanilide. This compound is cyclized with phosphorus pentoxide and phosphorus oxychloride according to the procedure of Example 13 to yield 11-(1-methyl-4-piperidyl)-2-methylthiobenz[b,f][1,4]oxazepine.

EXAMPLE 27

Preparation of 2-chloro-8-methyl-11-(1-methyl-4-piperidyl)dibenzo[b,f][1,4]thiazepine

The methods of Example 14 are repeated. Thus, 4-(p-chlorophenylthio)-m-toluidine is acylated with 1-methylisonipecotoyl chloride hydrochloride to give 4'-(p-chlorophenylthio)-1-methyl-m-isonipecotoluidide as in Example 14. This compound is cyclized in hot polyphosphoric acid as in Example 14 to give 2-chloro-8-methyl-11-(1-methyl-4-piperidyl)dibenzo[b,f][1,4]thiazepine.

EXAMPLE 28

Preparation of 8-methyl-11-(1-methyl-4-piperidyl)dibenzo[b,f][1,4]thiazepine

2-chloro-8-methyl-11-(1-methyl - 4 - piperidyl)dibenzo[b,f][1,4]thiazepine, prepared as in Example 27, is dissolved in ether and added to a suspension of magnesium in ether previously activated by treatment with a little ethylene dibromide. The resulting Grignard reagent is decomposed by cautious addition of water to yield 8-methyl-11-(1-methyl-4-piperidyl)dibenzo[b,f][1,4]thiazepine.

EXAMPLE 29

Preparation of 2-chloro-11-(1-methyl-4-propyl-4-piperidyl)dibenzo[b,f][1,4]thiazepine

1-methyl-4-propyl-4-cyanopiperidine is prepared and hydrolyzed to give 1-methyl-4-propylisonipecotic acid. This compound is converted to the acid chloride hydrochloride by the procedure described in Example 13, and condensed with 2-(p-chlorophenylthio)aniline to give 2'-(p-chlorophenylthio)-1-methyl-4 - propylisonipecotanilide. This material is cyclized in hot polyphosphoric acid by the method of Example 14, to yield 2-chloro-11-(1-methyl-4-propyl-4 - piperidyl)dibenzo[b,f][1,4]thiazepine.

EXAMPLE 30

Preparation of 2-chloro-11-(1-methyl-3-pyrrolidinyl)dibenzo[b,f][1,4]oxazepine

The methods described in Example 13 are used, and 2-(p-chlorophenoxy)aniline is treated with 1-methyl-3-pyrrolidinyl carbonyl chloride hydrochloride, by the procedure of Example 13, to give 2'-(p-chlorophenoxy)-1-methyl-3-pyrrolidinyl-carboxanilide. This compound is cyclized with phosphorus pentoxide in phosphorus oxychloride to give 2-chloro-11-(1-methyl - 3 - pyrrolidinyl)dibenzo[b,f][1,4]oxazepine.

14

EXAMPLE 31

Preparation of 2-chloro-11-(1-methyl-3-piperidyl)dibenzo[b,f][1,4]thiazepine

The methods of Example 14 are repeated. Thus, 2-(p-chlorophenylthio)aniline is acylated with 1-methylnipecotoyl chloride hydrochloride to give 2'-(p-chlorophenylthio)-1-methylnipecotanilide as in Example 14. This compound is cyclized in hot polyphosphoric acid, as in Example 14, to give 2-chloro-11-(1-methyl-3-piperidyl)dibenzo[b,f][1,4]thiazepine.

EXAMPLE 32

Preparation of 2-chloro-11-(1-methyl-2-piperidyl)dibenzo[b,f][1,4]thiazepine

The methods of Example 14 are repeated. Thus, 2-(p-chlorophenylthio)aniline is acylated with 1-methylnipecolyl chloride hydrochloride to give 2'-(p-chlorophenylthio)-1-methyl-nipecoanilide as in Example 14. This compound is cyclized in hot polyphosphoric acid as in Example 14 to give 2-chloro-11-(1-methyl-2-piperidyl)dibenzo[b,f][1,4]thiazepine.

EXAMPLE 33

Preparation of 11-(6-methyl-3-piperidyl)dibenzo[b,f][1,4]oxazepine

A solution of 1-carbobenzyloxy-6-methylnipecotic acid in tetrahydrofuran at 10° is treated with carbonyldiimidazole followed by p-phenoxyaniline. The mixture is refluxed and 1 - carbobenzyloxy - 6 - methyl-2'-phenoxy-nipecotanilide which forms, is isolated. This compound is cyclized with phosphorus pentoxide in phosphorus oxychloride according to the procedure of Example 13 to give 11 - (6 - phenyl - 3 - piperidyl)dibenzo[b,f][1,4]oxazepine.

EXAMPLE 34

Preparation of 11-(1-methyl-4-piperidyl)-2-nitrodibenzo[b,f][1,4]-oxazepine

The compound o-(p-nitrophenoxy)aniline is treated with 1-methylisonipecotoyl chloride hydrochloride by the procedure of Example 14 to give 1-methyl-2'-(p-nitrophenoxy)isonipecotanilide.

This compound is cyclized with phosphorus pentoxide and phosphorus oxychloride according to the procedure of Example 13 to give 11-(1-methyl-4-piperidyl)-2-nitrodibenzo[b,f][1,4]-oxazepine.

EXAMPLE 35

Preparation of benzyl 4-[o-(p-chlorophenylthio)phenyl]carbamoylpiperidine-1-carboxylate

A solution of 4.0 g. of 1,4-piperidinedicarboxylic acid 1-benzyl ester in 25 ml. of thionylchloride is warmed (45° C.) until the evolution of gas ceases. The solution is concentrated to dryness, suspended in 200 ml. of hexane, and reconcentrated to dryness. The acid chloride is then dissolved in 100 ml. of dry acetone.

The above solution is added dropwise to a solution of o-(p-chlorophenylthio)aniline base (prepared by dissolving 4.6 g. of the hydrochloride in a 10% aqueous potassium carbonate methylene chloride mixture, separating the phases, and evaporating the methylene chloride phase) in 100 ml. of dry acetone, and 2.4 g. of dimethylaniline is added. After stirring overnight, the solution is concentrated to dryness and the oily residue is triturated with a 10% potassium carbonate-methylene chloride mixture. The phases are separated and the organic fraction is washed with three 25-ml. portions of 6 N hydrochloric acid. The methylene chloride solution is dried (potassium carbonate) and concentrated to dryness to give an oil.

The oil is reprecipitated from aqueous acetone followed by crystallization from hexane to give pure benzyl 4-[o-(p-chlorophenylthio)phenyl carbamoyl]piperidine-1-carboxylate, melting point 111-113° C.

15**EXAMPLE 36****Preparation of N-(o-phenoxy)isonipectotanilide**

The procedure described in Example 35 is repeated and benzyl-4-(o-phenoxy)phenylcarbamoylpiperidine - 1-carboxylate is prepared from 1,4-piperidinedicarboxylic acid 1-benzyl ester and o-phenoxyaniline. It is obtained as an oil; I.R. 2.9 μ (amide NH), 5.85 μ (broad, carbamate and amide C=O), ca. 8.0-8.3 μ (C=O).

This oil is stirred with 48% hydrogen bromide in glacial acetic acid and concentrated to give N-(o-phenoxy)isonipectotanilide.

What is claimed is:

1. The compound, 2 - (o-aminophenylthio)-5-chlorophenyl 4-piperidyl ketone.

5

16

2. The compound, 2 - (o-aminophenylthio)-5-chlorophenyl 1-methyl-4-piperidyl ketone.

3. The compound, 2 - (o - aminophenoxy)phenyl 4-piperidyl ketone.
